DOBBY PATTERN CHAIN

Application filed July 10, 1931. Serial No. 549,960.

This invention relates to improvements in pattern chains for dobbies and it is the general object of the invention to provide improved connections between adjacent dobbey pattern chains.

The usual form of dobbey chain comprises a set of wooden bars into which are driven pegs to lift the dobbey fingers. A slotted cylinder grips the sides of the bars to feed them to the fingers, and links or loops connect the various bars together to form an endless chain. The loops have heretofore been secured to wires which extend through the bars and are bent to form eyelets. It is an important object of our invention to provide a larger connection between adjacent bars than is afforded by the wire without reducing the pegs' capacity of the bars.

It is a further object of our invention to provide a flat metal stamping which can be set into a bar and having holes to register with the peg receiving holes of the bar. The holes in the clip are preferably somewhat larger than the holes in the bar so that a slight mis-adjustment will not prevent the proper entry of the pegs.

It is another object of our invention to improve the dobbey bar by providing the same with a sheet metal clip which has attaching eyelets formed by striking lugs from the body of the clip and forcing said lugs into opposite sides of the dobbey bar to hold the latter against relative displacement with respect to the bar.

With these and other objects in view which will appear as the description proceeds, our invention resides in the combination and arrangement of parts hereinafter described and set forth in the claims.

In the accompanying drawing, wherein two forms of the invention are shown,

Fig. 1 is a rear view of two adjacent bars made according to the preferred form of our invention,

Fig. 2 is an end view taken in the direction of arrow 2, Fig. 1,

Fig. 3 is a top plan taken in the direction of arrow 3, Fig. 1,

Fig. 4 is an enlarged plan view of the clip,

Fig. 5 is an end view of the clip shown in Fig. 4,

Fig. 6 is a detail of one end of a dobbey bar having the modified form of our invention applied thereto, and

Fig. 7 is a vertical section on line 7—7 of Fig. 6.

Referring to Figs. 1 and 2, we have shown chain bars 10 which have rather broad left hand surfaces 11 and relatively narrow right hand surfaces 12. The surfaces are connected by inclined sides 13 and as shown particularly in Fig. 3 the end as well as the sides of each bar may be inclined as at 14. Each bar has extending therethrough a series of holes 15 which may be located as suggested in Fig. 1. The holes when arranged as set forth herein receive pegs for a double index dobbey and these pegs are set forth herein as at 16. It is to be understood that the order of the pegs in the successive bars of the chain determine the sequence in which the harnesses are raised and lowered and thereby regulate the pattern. The matter thus far described is old and forms no part of our present invention.

In carrying the preferred form of our invention into effect we provide a clip such as set forth more particularly in Figs. 4 and 5 and having a flat body portion 20 having perforations 21 slightly larger in diameter than the holes 15, but placed as to be in substantial register with certain of the latter. An opening 22 in one edge of the plate 20 as set forth in Fig. 4 corresponds to one of the holes 15.

Lugs 23 extend laterally from the body 20, being preferably at right angles to the latter before assembly. These lugs are disposed as suggested in Fig. 4 and are struck from and are integral with the body. Oppositely extending horns 24 are perforated as at 25 to receive connecting links 26 which attach the adjacent bars together.

Each end of each bar in the preferred form is provided with a slot 30 cut so as to be parallel to the faces 11 and 12 and preferably of such a depth that when the plate 20 is set therein the holes 21 and notch 22 will register with certain of the holes 15 of the corresponding chain bar. The lugs 23 may be bent in-

wardly as suggested at 31 in Fig. 2 so as to clinch the wood by penetration to prevent endwise movement of the clip with respect to the chain bar. When the pegs are to be applied to those holes 15 which are in register with the holes 21 or notch 22 no interference on the part of the body 20 will be experienced, and if the clip should be misplaced slightly in any direction the pegs can be inserted because of the fact that the holes 21 are larger than the holes 15.

The right hand edge of the body 20 as viewed in Fig. 4 is preferably held in tight contact with the right hand end of the slot 30 as shown in Figs. 1 and 3 while the lugs are being forced in place and there is therefore little or no likelihood that the clip will be able to turn.

In the modified form we provide a clip 40 having substantially parallel sides 41 extending through a closed slot 42 in bar 43 and parallel with the faces 44 and 45, respectively, and located preferably midway between them. Each end of the clip has struck therefrom a lug 46 to define an opening or eyelet 47. The lugs 46 are forced against the inclined surfaces 48 and preferably are embedded in the wooden bar to prevent transverse movement of the clip. The side walls of the slot 42 preferably engage the sides 41 of the clip and prevent longitudinal movement of the bar. This latter provision may be omitted where the lugs are forced into the inclined surfaces 48. Attaching links or loops 49 pass through the eyelets of two adjacent bars to connect them together. As in the preferred form the clip is provided with openings 51 which may align with certain of the smaller holes 50.

From the foregoing it will be seen that we have provided a simple form of clip for connecting together the various bars of a dobby pattern chain and that a metal to metal contact is secured which relieves the bars of strain. It will further be seen that the clip is formed of a single piece of metal having lugs integral therewith which engage parts of the bar to prevent transverse movement of the clip. It will be also seen that the lugs can be forced into the wood so as to prevent loss of the clip out of the open or free end of the slot 30 in the preferred form. In the modified form it will be seen that the lugs 46 form the eyelets 47 when struck from the body of the clip, and that the eyelets are aligned with the lugs so that no twisting strain exists tending to loosen the clip on the bar.

Having thus described our invention it will be seen that changes and modifications may be made therein by those skilled in the art without departing from the spirit and scope of the invention and we do not wish to be limited to the details herein disclosed, but what we claim is:

1. In a dobby pattern chain operating with pattern pegs, a chain bar having transverse

holes for the pegs, and a sheet metal clip secured to the bar to attach the same to adjacent bars and having perforations aligned with certain of the peg holes of the bar.

2. A dobby pattern chain bar having pattern peg holes therethrough and provided with an attaching clip extending transversely of the holes and having an opening registering with one of the holes.

3. A dobby pattern chain bar having holes therethrough for pattern chain pegs and provided with a sheet metal attaching clip extending through the bar and having a perforation aligned with one of the peg holes.

4. A dobby pattern chain bar having an attaching clip with integral lugs lying on opposite sides of the bar to prevent transverse movement of the clip on the bar, and attaching eyelets on the clip separate from the lugs.

5. A dobby pattern chain bar having holes therethrough for pattern chain pegs and provided with a sheet metal attaching clip extending through the bar and having a perforation aligned with one of the peg holes, and holding lugs on the clip to engage opposite sides of the bar to prevent transverse movement of the clip on the bar.

6. A dobby pattern chain bar having pattern element holes therethrough and provided with a clip having a perforation aligned with one of the holes, said clip having attaching eyelets on opposite sides of the bar.

7. A dobby pattern chain bar having pattern element holes therethrough and provided with a clip having a perforation aligned with one of the holes, said clip having attaching eyelets on opposite sides of the bar and said clip having integral lugs to engage the bar on opposite sides thereof.

8. A dobby pattern chain bar having pattern element holes therethrough and provided with a clip having a perforation aligned with one of the holes, said clip having attaching eyelets on opposite sides of the bar and said clip having integral lugs independent of the eyelets to engage the bar on opposite sides thereof.

9. A dobby pattern chain bar provided with an attaching clip having closed eyelets defined by striking bar engaging lugs from the clip.

10. A dobby pattern chain bar having a sheet metal clip extending therethrough, said clip having integral lugs struck therefrom into engagement with the bar, and attaching eyelets formed entirely by parts of the clip and defined in part by said lugs.

11. In a dobby pattern chain bar, a transversely extending sheet metal clip passing through the bar, eyelets formed on opposite ends of the clip, and lugs located between the eyelets and struck from the clip and having holding engagement with the bar.

12. In a dobby pattern chain bar, a clip extending transversely of the bar, lugs

formed on the clip, and eyelets formed by striking the lugs from the clip.

13. In a dobby pattern chain bar, a clip extending transversely of the bar, lugs formed on the clip, and eyelets formed by striking the lugs from the clip, said eyelets being in alignment with the lugs and the latter engaging the bar to prevent transverse movement of the clip relatively to the bar.

10 In testimony whereof we have hereunto affixed our signatures.
